Application April 28, 1932, Serial No. 608,054

4 Claims. (Cl. 62—4)

This invention relates in a general way to refrigerating apparatus and more particularly to control mechanisms for controlling the operation of refrigerating apparatus but is not limited in the scope of its application to controlling such apparatus since the invention is capable of a wide variety of practical applications in many fields.

The objects of our invention include the provision of an improved control mechanism for controlling the opening and closing of an electric circuit in response to pressure and temperature changes, the control mechanism being provided with an improved type of manual control for selectively varying the normal automatic operation of the mechanism without changing the normal adjustment thereof, the manual control being also capable of being moved so as to open the electric circuit by an improved mechanism independently of the normal automatic operation.

It is another object of the invention to provide a refrigerator having the entire refrigerating apparatus mounted upon a removable top wall of the food compartment, the control mechanism for the refrigerating apparatus being mounted upon the top wall and provided with a selective manual control accessible from the food compartment, the control mechanism being so constructed that it may remain intact and connected to the refrigerating apparatus when the top wall is removed or replaced.

It is still another object of the invention to provide a flexible connection between the pressure responsive means of a control mechanism and the arm usually operated thereby and a manual control acting positively to move the arm independently of the pressure responsive means for the purpose of providing a manual control of the means actuated by the arm independent of the pressure responsive means.

It is a further object of the invention to provide for a control having an automatic means for opening and closing an electric circuit and an overload means responsive to excessive flow of electric energy through the circuit, a selective manual control for the automatic means provided with a hollow operating shaft and a means extending through the hollow shaft provided with indicating means at its lower end for indicating the tripping of the overload means and also for resetting of the overload means.

Further objects and advantages of the present invention will be apparent from the following description, reference being had to the accom-

panying drawings, wherein a preferred form of the present invention is clearly shown.

In the drawings:

Fig. 1 is a fragmentary vertical sectional view through a portion of the refrigerator cabinet disclosing a vertical sectional view along the line 1—1 of Fig. 3 of our improved switch properly located within the cabinet; 5

Fig. 2 is a diagrammatic layout of the refrigerating apparatus mounted in the cabinet shown in Fig. 1 together with a wiring diagram of our improved switch; 10

Fig. 3 is a top view of our improved control switch;

Fig. 4 is a sectional view along the line 4—4 of Fig. 3; 15

Fig. 5 is a sectional view along the line 5—5 of Fig. 3; and

Fig. 6 is a fragmentary sectional view along the line 6—6 of Fig. 3. 20

Referring to the drawings and more particularly to Fig. 1 there is shown a fragmentary portion of a refrigerator cabinet generally designated by the reference character 20 having an insulated food compartment 21 therein to which access is had by means of the door 22 which is supported by the door jamb 23 which comprises a portion of the framework of the cabinet. Above the food compartment 21 there is provided an insulated removable top wall portion 24 which is supported by means of thick rubber gaskets 25 and 26 upon the framework of the cabinet. Above the removable top wall portion 24 is provided a machinery compartment 27. This removable top wall portion supports on its upper side a sealed motor compressor unit 28, of any suitable type, shown diagrammatically in Fig. 2, as well as a condenser 29 and a receiver 30. These elements, namely the sealed unit, the condenser and receiver comprise the refrigerant liquefying apparatus. Upon the underside of the removable insulated top wall 24 there is supported the evaporating means comprising an evaporator 31, shown diagrammatically in Fig. 2. 25

A control switch 32 having a platform 33 provided with supporting feet 34 is fastened upon the top of the removable wall portion 24. Our improved control switch is provided with a manual operated means 35 which extends downwardly through the removable top wall portion 24 and is provided with a manually operable dial 36 at its lower end. A recess 37 is provided on the underside of the removable top wall portion 24 to provide for this manually operable dial 36. This recess provides sufficient 30 35 50 55

clearance for one desiring to operate the manual operating means to grasp the dial firmly and rotate it conveniently. The removable top wall portion is provided with insulation 38 which is held between upper and lower sheet metal walls 39 and 40. A rubber sealing bushing 41 is provided for sealing the opening through the upper sheet metal wall 39 through which the manual operating means 35 projects, and a similar rubber bushing 42 is provided for the opening in the lower sheet metal wall 40. These rubber sealing bushings prevent the access of air and moisture to the insulation 38 between the upper and lower sheet metal walls 39 and 40 and in this way the insulation is protected.

Referring now more particularly to Fig. 2, there is shown diagrammatically, a complete refrigerating system including the control means, all of which are mounted on the removable top wall portion 24 of the cabinet 20 without any connection to any other portion of the refrigerator cabinet, so that this top wall portion together with all of the portions of the refrigerating apparatus including a control means may be removed without disturbing any of the fluid or electrical connections or any other part of the apparatus. The sealed unit 28 contains a compressor 45 of any suitable type for compressing the refrigerant and for forwarding the refrigerant through a supply conduit 46 to the condenser 29 where the refrigerant is condensed and collected in the receiver 30. From the receiver 30 the refrigerant is forwarded through the conduit 47 to an expansion valve 48 of any suitable type which permits the flow of liquid refrigerant into the evaporator 31 where the liquid refrigerant under reduced pressure absorbs heat from the food compartment 21 and vaporizes, which vapor is returned to the compressor 45 through the return conduit 49.

The compressor 45 is preferably driven by an electric motor 50 also located within the sealed unit 28, which motor has a squirrel cage rotor 51 directly connected to the compressor 45. The motor 50 is provided with a running winding 52 and a starting winding 53. The motor is also preferably provided with a separate exciting winding 54 for actuating the starting relay which is necessary in single phase induction motors.

The elements of our improved switch are also shown in Fig. 2. These elements comprise a thermostatic switch 55 actuated by a thermostatic bulb 56 located in the food compartment 21 adjacent the evaporator 31. For protecting the windings of the motor 50 there is provided a compensated bimetallic overload means 57 having a pivoted bimetallic strip 58 which is heated by a heater 59 through which the current to the motor 50 passes. The bimetallic strip 58 holds the contact arm 60 in closed circuit position normally, but when an excessive amount of current flows through the heater 59, the bimetallic strip 58 will trip outwardly to release the contact arm 60 and to separate the contacts to open the motor circuit. A second bimetallic strip 61 is connected to the strip 58 at one end and is held stationary by an adjustment device 62 at its other end. This second bimetallic strip 61 compensates the overload device for changes in room temperature.

A starting relay, generally designated by the reference character 63, comprising a contact arm 64, an armature 65, and a relay coil 66, is provided for opening and closing the starting winding circuit. One of the power lines 67 is first con-

nected so that the current will flow through the heater 59, thence through the contact arm 60 and through the overload contacts of the overload relay 57 to the thermostatic switch 55. From thence the current flows through an electrical conductor 68 which conducts the electric current to the conductor 69 which leads to the contacts of the starting relay 63 from which the electric current flows through an electric conductor 70 to the starting winding 53 which is connected to the other wire 71 of the power line. Another electrical conductor 72 is connected to the conductor 68 and conducts electric current to the main winding 52 which is also connected to the wire 71. A branch electrical conductor 73 connects the conductor 68 to the relay coil 66 and another electrical conductor 74 connects the relay coil 66 with the relay exciting coil 54 located in the motor windings. The relay coil 54 is also connected to the electrical conductor 72 within the sealed unit 28. The relay exciting circuit, comprising the relay coil 66, the relay exciting coil 54 and the electrical conductors 73, 74 and 72 may be entirely separate from the motor circuit but a portion of the motor circuit, namely the electrical conductor 72 has been used as a part of this circuit in order to eliminate one lead-in bushing to conduct the electric current through the housing of sealed unit 28.

Referring now more particularly to the figures 30 showing the practical embodiment of our improved control switch, there is shown particularly in Fig. 5, a generally U-shaped supporting bracket 80, which is mounted upon the platform 33 and surrounds a bellows 81 which is expanded and contracted by the expansion and contraction of a volatile fluid within the thermostatic bulb 56 shown in Fig. 2 which is connected to the bellows 81 by means of a connecting conduit 79. The U-shaped bracket 80 is provided with rearwardly extending flanges 83, which extend upwardly and have a bellows follower 82 pivoted to the flanges 83 by means of the pin 84. The follower 82 is provided with ears 85 which receive the pivot pin 84 and which are located between the flanges 83. The follower 82 has a downwardly projecting pin 86 which engages the upper closed end of the thermostatically operated bellows 81. The free end of the follower 82 is provided with a notch which receives an upwardly extended portion 87 of the U-shaped bracket 80, which portion is provided with abutment means for limiting the movement in either direction of the free end of the follower 82.

On top of the follower 82 there is supported a 55 spring retainer 88 which supports the lower end of an adjusting spring 89. The upper end of the adjusting spring 89 is supported by a knurled spring retainer 90 threaded upon a short threaded pin 91 which is riveted to an adjustment hinge 92 provided with ears 93 at its opposite end and pivoted by means of a pin 94 to the upper end of the flanges 83. The tension of the adjusting spring may be varied by rotating and thus moving upwardly or downwardly the knurled spring retainer 90 to change the tension of the adjusting spring. The ears 93 are located on the outside of the flanges 83. Pivoted to the flanges 83 by means of the pin 84 is a main operating arm or lever 95 of a general inverted L-shaped form 60 as shown in Fig. 3. This arm extends around the outside of the flanges 83. This arm is connected to the bellows follower 82 by being resiliently held against an ear 96 which extends from the bellows follower 82. The operating arm of lever 95 65

is resiliently held in engagement with the ear 96 by means of a hook 97 which engages the lower side of the operating arm 95 and which passes through the ear 96 and is provided with a coil 5 spring 98 of the compression type which presses against a washer 99 and a cotter pin 100 which is held by the upper end of the hook 97. In this way the arm 95 is held in normal engagement with the ear 96 of the follower 82 so that the arm 10 will normally follow the movements of the bellows follower 82.

The free end of the operating arm of lever 95 is connected to a toggle switch mechanism. For this purpose, a member of a suitable moulded insulating material 101 is fastened to the free end of the operating arm 95 by a bolt 102. This member 101 of insulating material is provided with a pair of notches 103, best shown in Fig. 6, which support the knife edges at the forked end of a flat wishbone shaped secondary lever 104 in order that this secondary lever may be pivoted to the operating arm or primary lever 95. In order to control the movement of the free end of the wishbone-shaped secondary member, a stop member 20 25 105 is provided with a U-shaped portion 106 with which a rubber bumper 107, held in the end of the secondary lever 104, engages to limit the movement of the free end of the secondary lever.

The secondary lever 104 is connected by means 30 of a tension coil spring 108 to an upwardly extending arm 109 of a pivoted switch contact member 110. The switch contact member 110 has at its other end another upwardly extending arm 111 which is pivoted to the member 105 by having inwardly projecting prongs 112 extending into apertures in the opposite sides of the member 105. On its underside, the contact member 110 has a leaf spring 113 which is riveted at 114 to a projecting end portion of the switch contact member 110. 40 The leaf spring 113 has a switch contact 115 riveted to its free end. The switch contact member 110 is provided with an aperture directly above the switch contact 115 to receive the upper riveted portion of this contact. The leaf spring 113 is 45 limited in its downward movement by the stop member 116 which passes through an aperture in the leaf spring 113 and is riveted to the switch contact member 110. The leaf spring 113 is tensioned so as to resiliently press against the stop member 116. By this spring mounted construction of the contact 115, a more sudden and rapid engagement and disengagement of this contact is obtained with the stationary contact 117 with which it cooperates. In this double toggle switch 50 mechanism, when the pivot point 103 crosses the center line of the coil spring 108, the stationary lever 104 is tripped from one of its limiting positions to another of its limiting positions, and thereby the coil spring 108 will throw or pull the 55 switch contact member 110 from one of its limiting positions to another of its limiting positions. The movement of the switch contact member 110 is limited in moving to closed circuit position by the set of switch contacts 116 and 117 which engage each other and compress the leaf spring 113 60 against the switch contact member 110. In the opposite direction or opening movement of the switch contact member 110 there is provided an arm 118 extending from the U-shaped abutment member 106 which is provided with a set screw 119, the lower end of which engages the switch contact member 110 in order to limit its upward movement.

The maintenance of the proper differential be- 70 tween the opening position of the switch con-

tacts and the closing of the switch contacts is determined by the position of the free end of the secondary lever 104. Inasmuch as the rubber bumper is subject to some wear and is somewhat plastic, it follows that under some conditions this wear might cause a change in the differential of the switch after a period of use. In order to avoid such a possibility we have provided tripping pins 120 and 121 which form part of the abutment member 106. It will be understood that the angularity of the secondary lever 104 is greatest immediately after tripping from one position to another, and is the least when the secondary lever is ready to trip from one position to another. In this way, when the secondary lever 104 is tripped, 10 the rubber bumper 107 will engage the abutment member 106, and in this way the contact of the secondary member with the abutment member will be silenced. By reason of the greater angularity when the secondary lever comes into contact with the abutment member, only the rubber bumper 107 will contact with the abutment member 106 and the secondary lever 104 will not at this time come into engagement with one of the stopping pins 120 or 121. However, as the toggle mechanism approaches tripping position and the secondary lever 104 approaches in alignment with the coil spring 108, the angularity of the secondary lever 104 is reduced and the secondary lever will engage one of the stopping pins 120 or 121, whichever the case may be, and these stopping pins will hold the secondary lever 104 in proper position to be tripped. At this time the rubber bumper will be lifted free from the abutment member 106 so that the position of the free 20 25 30 35 40 45 50 55 60 65 70 75 end of the secondary lever at this time is entirely dependent on the location of the stopping pins. Inasmuch as the stopping pins are made of metal and are not subject to any impact, they will maintain their shape indefinitely and the free end of the secondary lever will always be held at the proper time in proper position for tripping.

In order to provide an adjustment for changing the differential of the switch mechanism, there is provided a tension coil spring 123, connected 45 at its lower end to a pin 124 fixed to the platform 33 and connected at its upper end to a threaded adjusting pin 125, which is provided with a nut 126 threaded thereon which normally rests upon a supporting arm 127 extending from the upwardly extending portion 87 of the U-shaped supporting bracket 80. The nut 126 has a downwardly extending portion 128 which is adapted to engage an ear extending from the bellows follower 82 when the bellows follower 82 is in its upper position. When the bellows follower 82 is in its lower position, as shown in Fig. 5, the bellows follower 82 is not in engagement with the abutment portion 128. In this way, by exerting a force upon one limit of the movement of the bellows follower 82 and not upon the other limit, the temperature or pressure differential may be increased, or if the force is reduced, the differential is reduced. A range adjustment is also provided by varying the tension of the coil spring 89 by raising or lowering the threadedly mounted knurled upper spring retainer 90.

Upon the upper end of the stop or supporting member 105 there is mounted, by means of the screw 130, a leaf spring 131 which carries at its free end an overload contact 132, which is riveted thereto. The contact 132 is adapted to engage a cooperating contact mounted upon the lever 133, which is pivoted by means of the pin 134 to the overload supporting bracket 135 which is 75

mounted upon a sub-base 136 which is preferably of some suitable moulded insulating material. The pivoted lever 133 is normally held in its uppermost position with its contact 138 in engagement with the contact 132 by means of a bimetallic strip 139, mounted upon a block of insulating material 140 which is pivoted by means of a pin 141 to a bracket 142 mounted on the sub-base 136. Also fixed to the block 140, but separate from the bimetallic strip 139, is a second bimetallic strip 143 which compensates for variations in room temperature. The bimetallic strip 143 is held at its free end by a screw 144 which is threaded into a strip of metal 145 which projects from the end of the bracket 142. A small coil spring 146 holds the free end of the bimetallic strip 143 in engagement with the head of the screw 144.

A heater 147 of nickel-chromium wire formed into a serpentine shape is riveted to the bimetal strip 139 and is thereby held at a fixed distance therefrom. This heater 147 corresponds to the heater 59 shown in Fig. 2. When an excessive amount of current flows through the heater 147, the bimetal strip 139 will be bent sufficiently out from under the lever 133 to allow the lever 133 to fall downwardly and to separate the overload contacts 132 and 138 to break the motor circuit. Inasmuch as the strip 143 always compensates the room temperature, the strip 139 will be always responsive to the heating action of the current flowing through the motor and in this way injury to the motor 50 will be prevented thereby.

In order to provide a convenient way of indicating the tripping of the overload switch as well as to provide a convenient way for resetting the same, an arm or lever 150, pivoted by means of the screw 151 to the supporting bracket 135, is provided with pins 153 and 152 on either side of the lever 133. The lever 150 has a metal strip 154 connected thereto which is connected by means of a pivot pin 155 to a collar 156 (see Fig. 1) which is held in place on a vertical rod 157 by means of a set screw 158. The vertical rod 157 extends downwardly through the center of the hollow shaft 35 and has a red button 159 at its lower end, a small portion of which is exposed beneath the manual operating dial 36. When the overload mechanism is tripped, the lever 133 will fall, engaging the lower pin 153 mounted on the lever 150 and the weight of the shaft 157 and the lever 150 will cause the shaft 157 to drop until stopped by the spacing members 160 so that a considerable length of the red button 159 will appear beneath the manual operating dial 36, indicating that the overload mechanism has tripped. In order to reset the overload mechanism, the red button is pushed upwardly, lifting the lever 150 which causes the lower pin 153 to raise the lever 133 and allow the bi-metal strip 139 to spring back to its position beneath the lever 133. In this way a convenient mechanism is provided for resetting the overload mechanism.

The cold control mechanism is operated by the manual operable dial 36 and the hollow shaft 35 which is rotatably mounted on the platform 33. The upper end of the hollow shaft 35 fits within the collar 162 which is provided with a flange 163 at its lower end and a double threaded portion 164 at its upper end. The collar 162 is caused to rotate with the shaft 35 by means of a set screw 165. A nut 166 provided with a double thread is mounted on the threaded portion 164 of the collar 162, and seats upon the bottom portion of a tilted U-shaped link 167

(see Figs. 1 and 4). The top portion of the U-shaped link 167 connects with an arm 168 extending from the adjustment hinge 92. This arm 168 extends through an aperture 169 in the side of the link 167 and has a turned up end which extends into an aperture 170 in the top of the link 167.

By rotating the shaft 35, the double threaded screw 164 raises or lowers the double threaded nut 166 which is held from rotation by the bracket 167 (as shown in Fig. 1), thus raising or lowering the adjustment hinge 92 to decrease or increase the tension upon the range adjusting coil spring 89 to provide a cold control effect.

The bushing 162 is provided with a collar 171 which is riveted thereto to hold the bushing in position. This collar 171 is provided with an upwardly projecting ear 172 which, when the manual operating dial 36 is moved to "off" or defrosting position, engages a depending portion 173 which is soldered or welded to an outwardly extending portion 174 of the main operating lever 95 to become an integral part thereof. When the defrosting ear 172 engages the arm 173, the operating arm 95 will be moved downwardly and held in its lower position by the defrosting ear. When this is done, the operating lever or arm 95 will move away from the abutment 96 against the tension of the spring 98. In this way the operating arm is moved independently of the bellows 81 or the bellows follower 82 in order to hold the switch contacts 116 and 117 separated for defrosting purposes.

The starting relay is mounted upon the sub-base 136 which is preferably made of molded insulating material. The starting relay is provided with an L-shaped member 180 of magnetic material which supports an electro-magnet 181. At the upper end of the L-shaped member 180 there is pivotally mounted a tilting armature 182. The tilting armature 182 is normally held in extreme counter-clockwise position away from the electro-magnet 181 and against a stop 183 of insulating material by a coil spring 184. The coil spring 184 is connected at its lower end to a pin 185 fixed to the L-shaped bracket 180 and is connected at its upper end to a threaded pin 186 provided with a nut 187 which rests upon the upper surface of the tilting armature 182. When the armature 182 is rotated in a clockwise direction by the electro-magnet 181, an ear 188 at one end engages a leaf spring 189 (see Fig. 3) to separate a set of relay contacts, one contact 190 of which is riveted to the end of the leaf spring 189 and the other contact 191 of which is riveted to a bracket 192 which is provided at its lower end with binding screws 193. When the compressor motor is idle, the relay contacts 190 and 191 will be in closed position. When the thermostatically controlled switch contacts are closed to close the circuit, very little electric energy is generated within the separate winding 54. As the motor speeds up, the generation of the electric energy by the winding 54 increases rapidly and finally becomes sufficient in amount to cause the electro-magnet 181 to attract the armature 182 against the tension of the coil spring 184 to open the relay contacts 190 and 191. The tension of the spring 184 is so calibrated that the relay contacts 190 and 191 will be opened at the desired tripping speed.

The switch is enclosed by a metal cover 195 which has its lower edge engaging the flange 196 surrounding the edge of the platform 33. The cover is secured to the platform 33 by a nut 198.

threaded upon a long vertical pin 199 which has its lower end riveted to the platform 33.

While the form of embodiment of the invention as herein disclosed constitutes a preferred form, it is to be understood that other forms might be adopted, all coming within the scope of the claims which follow.

What is claimed is as follows:

1. Refrigerating apparatus including an insulated refrigerator cabinet having an insulated removable wall portion supporting a refrigerating apparatus, and control means mounted upon one side of said removable wall portion for controlling the operation of the refrigerating apparatus, said control means having manual operating means for selectively varying the operation thereof, said manual operating means having a portion extending through said removable wall portion and having a manipulating portion connected to said extending portion and exposed on the other side of said removable wall portion.
2. Refrigerating apparatus including an insulated refrigerator cabinet having an insulated removable wall portion, a refrigerating apparatus supported thereon, a food compartment adjacent the removable wall portion, control means mounted upon one side of said removable wall portion for controlling the operation of the refrigerating apparatus, rotatable shaft means extending from said control means through said removable wall portion, sealing means between said shaft means and said removable wall portion, and a manually operable dial upon the end of said shaft means exposed within the food compartment for selectively varying the operation of said control means.

3. Refrigerating apparatus including an insulated refrigerator containing a food compartment provided with an insulated removable wall portion supporting a refrigerating system, said system including control means mounted outside of said food compartment upon one side of said removable wall portion, said control means having manual regulating means extending through the removable wall portion into the food compartment and provided with manual manipulating and indicating means at the end thereof within the food compartment, said control means having means controlled by said manual manipulating means for controlling the starting and stopping of the refrigerating system and for varying the average temperature within the food compartment.

4. Refrigerating apparatus including an insulated refrigerator cabinet having an insulated removable horizontal wall portion supporting a refrigerating apparatus, and control means mounted upon one side of said removable horizontal wall portion for controlling the operation of the refrigerating apparatus, said control means having manual operating means for selectively varying the operation thereof, said manually operating means having a vertical shaft extending through said removable horizontal wall portion and having a manipulating means connected to said vertical shaft and exposed on the other side of said horizontal removable wall portion.

GEORGE C. PEARCE.
DONALD FORD ALEXANDER.
